UNITED STATES PATENT OFFICE

152,287

DESIGN FOR A FISH LURE

Melkiah Edward Pope, Montrose, Calif.

Application October 21, 1947, Serial No. 142,042

Term of patent 3½ years

(Cl. D31—4)

To all whom it may concern:

Be it known that I Melkiah Edward Pope, a citizen of the United States, residing in Montrose, in the county of Los Angeles and State of California, have invented a new, original, and ornamental Design for a Fish Lure, of which the following is a specification; reference being had to the accompanying drawings, forming a part thereof.

Figure 1 is a side elevation of a fish lure, showing my new design;

Figure 2 is a top plan view thereof; and

Figure 3 is an end elevation thereof.

I claim:

The ornamental design for a fish lure, as shown.

M. EDWARD POPE.
